Irvin G. Spigelman, Chicago, Ill., assignor to Chicago Printed String Company, Chicago, Ill., a corporation of Delaware

Filed Dec. 3, 1957, Ser. No. 700,390

8 Claims. (Cl. 229—52)

This invention relates to an improved article support and more particularly to an improved handle having greatly enhanced strength and versatility which may be especially adapted for use with heavy cartons and the like.

In the past few decades, the distribution of many consumer products has been in small packages weighing only a few ounces. Such small packages could be readily packed into kraft bags and the like for transportation by the purchaser. However, it was necessary to repurchase the goods at very short intervals. Furthermore, such packaging techniques are expensive, the cost of the package often equaling or exceeding the actual value of the goods contained therein.

A typical example of a product in this category is soap in granulated or flake form. Soap and modern detergents are used in large quantities by the housewife and are relatively bulky and heavy. Thus the housewife has heretofore required many of the conventional small boxes in order to carry on her normal daily routine and thus purchased the goods at regular, very short intervals. The manufacturers of soap and detergents, recognizing this, have recently introduced large size cartons containing in the order of twenty to twenty-five pounds of soap or detergent in granulated form. While these cartons greatly improve the efficiency of packaging and have resulted in lower cost to the consumer, they are difficult to handle and the housewife objects to one such carton substantially filling her entire shopping bag. Thus, several manufacturers have attached handles of various types to such cartons, but all of the handles heretofore proposed have been expensive, weak or cumbersome during shipping and handling prior to purchase by the ultimate consumer.

Thus, it is one important object of this invention to provide an improved article support having greatly enhanced tensile and impact strength.

It is another object of this invention to provide an improved article support which is simple and inexpensive in construction.

It is still another object of this invention to provide an improved article support which may be readily manufactured by automatic or continuous processes.

Another object of this invention is the novel method by which article supports of the type described herein may be manufactured.

It is still a further object of this invention to provide a separate handle unit which may be readily inserted in cartons and the like after such cartons have been filled.

It is still a further object of this invention to provide an improved carton handle which will not interfere in any way with normal storage, shipping and handling thereof.

It is an additional object of this invention to provide an improved carton handle wherein no tear or shear stresses are of importance but all stresses are distributed as tensile forces substantially parallel to the joints and webs of the construction.

Further and additional objects of this invention will

2

appear from this specification, the accompanying drawing and the appended claims.

In one form of this invention a handle unit especially adapted for insertion under two of the top flaps of a cardboard carton is provided. More particularly, the handle unit consists of a cardboard web having an elongate flexible handle secured thereto at its ends with the end portions folded under the web and with transverse reinforcing strips attached thereto.

10 For a more complete understanding of this invention reference will now be made to the accompanying drawing wherein:

Fig. 1 is a perspective view of a carton comprising and incorporating one embodiment of this invention;

Fig. 2 is an exploded perspective view of the embodiment of Fig. 1 with the handle unit shown in the removed position;

Fig. 3 illustrates the first step in the manufacturing process described herein;

20 Fig. 4 illustrates a subsequent step in the manufacturing process of this invention.

Fig. 5 is an end view of the handle unit of Fig. 2; and

25 Fig. 6 is a cross sectional view of the flexible elongate handle taken on the line 6—6 of Fig. 5.

Referring now to the drawing and more particularly to Figs. 1 and 2 a carton 10 incorporating handle unit 12 is illustrated. The unit 12 has an elongate flexible handle 14 secured thereto in a novel manner and the 30 unit is disposed between sets of opposite carton flaps 16 and 18. In assembling the carton and unit the flaps 16 are first folded in the open top 20 of carton 10, after which the handle unit 12 is placed thereon.

The second set of opposed flaps 18 are cut away to 35 provide space for the flexible handle 14. The cuts include large transverse end cuts 22 and slightly cut-away central portion 24 so that when the flaps 18 overlie the handle unit 12 as shown in Fig. 1 the elongate handle 14 passes through the large cuts 22 readily and lies 40 within the cut-away portion 24 between the flaps 18. The unit 12 may be secured to the flaps 16 with any appropriate adhesive, if desired. The flaps 18 are similarly adhesively secured to handle unit 12.

The handle 12, as partially shown in Fig. 2, is of 45 unique construction whereby it possesses great tensile strength, impact strength, and rigidity. The unit 12 consists of a central rigid web 26 which may be formed of stiff cardboard or the like and two underlying end portions or wings 28 folded under web 26. As will be 50 described in greater detail hereinafter the flexible handle 14 is secured to the wings 28 and transverse reinforcing strips are associated therewith.

Referring now to Figs. 3 and 4, the method of producing the handle unit 12 will be described in detail. A 55 continuous elongate strip of cardboard 30 is passed in the direction of arrow 29 through appropriate machinery wherein continuous strips of reinforcing strand material 32 and 34 are secured to the cardboard parallel to the elongate edges 31 and spaced therefrom. The reinforcing strips 32 and 34 may be of any appropriate material, although in one particular embodiment of this invention a tape composed of sixteen ends of 1800 denier rayon were found to be especially appropriate. Although the strands may be secured to the cardboard 30 with any 60 appropriate adhesive, a vinyl emulsion was found satisfactory in the described embodiment.

Immediately following the application of reinforcing strips 32 and 34 the web 30 is transversely cut by any appropriate means such as a conventional slitting machine. The cardboard is cut along broken lines 36 to 70 form individual unit webs 26. The webs 26 are then

passed in the direction indicated by arrow 38 through a second manufacturing stage where the elongate handle 14 is secured thereto.

The handle 14 is placed over web 26 with looseness or freedom therebetween whereby in subsequent use the fingers of a purchaser may be passed between the web and handle. The ends 40 of handle 14 are secured to the wings 28 in any appropriate manner. A special machine may be provided for automatically forming the arcuate central portion of handle 14 and coincidentally gluing ends 40 to wings 28. Thereafter wings 28 are folded under web 26 along lines 42, producing the handle assembly 12 illustrated in Fig. 5. While the method of manufacture has been described as it is especially adapted for automatic machinery, it should be clear that any individual step, or the entire operation, may be performed manually.

In Fig. 5, it can be seen that the elongate handle 14 is loosely disposed above web 26 and is secured thereto along the underside thereof by securing the ends 40 to the wings 28 by adhesive means. Reinforcing strips 32 and 34 are shown as a plurality of strand ends as already described above. The handle 14 may be constructed of the same strands utilized for reinforcing strips 32 and 34, that is, a plurality of 1800 denier rayon strands disposed in independent aligned relationship. In the preferred embodiment the strands are enclosed in a cover formed of paper or the like.

Fig. 6 illustrates the preferred cross section of handle 14. Handle 14 is formed by passing a plurality of strands 44 through a machine by which an adhesive such as the vinyl emulsion described above is applied to the strands, after which a paper wrapper 46 is formed thereabout. The wrapper 46 is formed of a continuous elongate strip of material. The edges 48 of the strip are first folded to overlie adjacent portions 50 of the strip, after which the edges and adjacent portions are folded about the strands 44 forming a complete encasement thereover.

The handle produced by the process set forth above is unique in that it is well adapted for continuous or automatic production on well known or readily constructed machines. All of the operations are initially performed on one side of the main web of the unit, after which the ends thereof are folded under. The construction has unusual strength in that there is no tendency to draw the handle away from the web, but all forces acting thereon are tensile forces applied substantially parallel to the joints between the handle and wing portions. Moreover, the end portions 40 of handle 14 are reinforced by transverse strips 32 and 34 whereby the tensile forces acting on the handle are distributed through a reinforcing T consisting of the handle ends 40 and the outwardly extending portions of reinforcing strips 32 and 34. This construction also greatly aids in the support of weight by the carton 10. As the weight is uniformly distributed along the edges of the handle unit through strips 32 and 34, the weight is distributed as pure tensile forces in the walls of the carton and there is little or no tearing or shearing forces resulting from the use of this handle.

While one particular embodiment of this invention has been described in intricate detail it will be clear that various modifications will immediately appear to one skilled in this art. For example the benefits of the flexible handle and rigid web can be attained irrespective of the particular materials which are employed. The web, for example, may be of cardboard as suggested or might be of paper, appropriate plastics or thin metal film. Similarly, the flexible handle 14 may be of the construction described in detail herein or might be of cloth, paper, rope or the like construction. The particular described embodiment made of the materials suggested has strength more than adequate for the support of cartons containing twenty-five pounds of material.

Furthermore, the strength is adequate to support sharp impact forces in the order of one hundred pounds. The particular materials selected, the size of the handle unit and precise configuration will be determined by the article to be supported and the strength required.

Without further elaboration, the foregoing will so fully explain the character of my invention that others may, by applying current knowledge, readily adapt the same for use under varying conditions of service, while retaining certain features which may properly be said to constitute the essential items of novelty involved, which items are intended to be defined and secured to me by the following claims.

I claim:

15. An article support comprising a stiff rectangular web, stiff integrally formed wings extending from two parallel edges of said web and folded to partially overlie one surface thereof, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
20. An article support comprising a stiff rectangular web, stiff integrally formed wings extending from two parallel edges of said web and folded to partially overlie one surface thereof, reinforcing means secured to each of said wings adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
25. An article support comprising a stiff rectangular web, stiff integrally formed wings extending from two parallel edges of said web and folded to partially overlie one surface thereof, reinforcing means secured to each of said wings adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
30. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
35. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
40. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
45. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
50. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
55. An article support comprising a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being secured to said wings whereby said handle loosely overlies said other surface, said ends of said handle being formed over said two parallel edges with the associated wings.
60. An article support comprising a container having an open top and flap portions hinged to said container along spaced substantially parallel edges of said open top to overlie said open top, a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a covering surrounding said strands.
65. An article support comprising a container having an open top and flap portions hinged to said container along spaced substantially parallel edges of said open top to overlie said open top, a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a covering surrounding said strands.
70. An article support comprising a container having an open top and flap portions hinged to said container along spaced substantially parallel edges of said open top to overlie said open top, a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a covering surrounding said strands.
75. An article support comprising a container having an open top and flap portions hinged to said container along spaced substantially parallel edges of said open top to overlie said open top, a stiff rectangular web, stiff integrally formed wings extending from two parallel edges of said web and folded to partially overlie one surface thereof, reinforcing means on each of said wings comprising a plurality of independent strands and an adhesive securing said strands to said wing adjacent to said web and extending parallel to said two edges, and a covering surrounding said strands.

a flexible elongate handle overlying the other surface of said web and having a length substantially greater than said web, the ends of said handle being secured to said wings whereby said handle loosely overlies said other surface, said ends of said handle being formed over said two parallel edges with the associated wings, said handle comprising a plurality of independent strands, an adhesive securing said strands together, and a covering surrounding said strands, said web being disposed in said open top with said flap portions thereover whereby said handle is exposed adjacent the juxtaposed free edges of said flap portions.

6. An article support comprising a carton having a bottom, side walls, and an open rectangular top, flap portions hinged to the four edges of said carton defining said top, a stiff rectangular web, stiff integrally formed wings extending from two parallel edges of said web and partially overlying one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being formed over said two parallel edges and secured to said wings whereby said handle loosely overlies said other surface, said handle comprising a plurality of independent strands, an adhesive securing said strands together, and a covering surrounding said strands, said web being disposed in said open top overlying two opposed flap portions, two of said flap portions overlying said web and being secured thereto whereby said handle is exposed adjacent the juxtaposed free edges of said flap portions.

7. An article support comprising a carton having a bottom, side walls, and an open rectangular top, flap

25

30

portions hinged to the four edges of said carton defining said top, a stiff rectangular web, stiff integrally formed wings extending from two parallel edges of said web and partially overlying one surface thereof, reinforcing means on each of said wings comprising a plurality of independent strands and an adhesive securing said strands to said wing adjacent to said web and extending parallel to said two edges, and a flexible elongate handle overlying the other surface of said web and having a length substantially greater than said web, the ends of said handle being formed over said two parallel edges and secured to said wings whereby said handle loosely overlies said other surface, said handle comprising a plurality of independent strands, an adhesive securing said strands together, and a covering surrounding said strands, said web being disposed in said open top overlying two opposed flap portions and secured thereto, two of said flap portions overlying said web and being secured thereto whereby said handle is exposed adjacent the juxtaposed free edges of said flap portions.

8. The article support of claim 7 wherein said handle comprises a plurality of rayon strands secured together with an adhesive formed of a vinyl emulsion and surrounded by a paper cover.
